(57) **CLAIM**

The ornamental design for a charging station, as shown and described.

DESCRIPTION

FIG. 1 is a front view of a charging station, showing our new design;

FIG. 2 is a rear view thereof, which is a mirror image of the front view;

FIG. 3 is a top view thereof;

FIG. 4 is a bottom view thereof;

FIG. 5 is a right side view thereof;

FIG. 6 is a left side view thereof; and,

FIG. 7 is a top, front and right side perspective view thereof. The broken lines in the drawings illustrate portions of the charging station that form no part of the claimed design.

1 Claim, 7 Drawing Sheets
